Primary Examiner — Stella Reid*Assistant Examiner* — Keli L Hill(74) *Attorney, Agent, or Firm* — Jones Waldo Holbrook & McDonough**CLAIM**

The ornamental design for a portable video media device holder, as shown and described.

DESCRIPTION

FIG. 1 is a front perspective view of the presently claimed design.

FIG. 2 is a side view of the presently claimed design.

FIG. 3 is an opposite side view of the presently claimed design.

FIG. 4 is a front view of the presently claimed design.

FIG. 5 is a rear view of the presently claimed design.

FIG. 6 is a top view of the presently claimed design; and,

FIG. 7 is a bottom view of the presently claimed design.
